UNITED STATES PATENT OFFICE.

WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

PERCUSSIVE TOOL.

1,324,078.

Specification of Letters Patent.

Patented Dec. 9, 1919.

Application filed December 26, 1918. Serial No. 268,341.

To all whom it may concern:

Be it known that I, WILLIAM A. SMITH, a citizen of the United States, residing at Easton, in the county of Northampton and State of Pennsylvania, have invented a certain new and useful Improvement in Motor-Rotation Percussive Tools; of which the following is a specification.

This invention relates to percussive tools, and in particular to a form of percussive tool having means for rotating a drill steel or other device adapted to be used in said tool.

The objects of the present invention are to provide a percussive tool which, in the example chosen for illustration, is a hammer drill, with a rotating motor for rotating the drill, the motor being mounted in a detachable casing on one side of the rear end 20 of the tool.

A further object of the invention is to provide improved means for securing the motor casing in position.

With the above and other objects in view, my invention consists in the features of construction and operation set forth in the following specification and illustrated on the accompanying drawings, forming a part hereof, in which:

Figure 1 shows a top plan view of the complete percussive tool, parts being shown in section;

Fig. 2, shows a longitudinal elevation of the tool taken in section;

Fig. 3, shows a section of the rotating motor and casing taken on the line 3—3 of Fig. 2.

Referring more particularly to the figures of the drawing, 1 refers to the cylinder of the percussive tool in which a piston or hammer of any well known type is adapted to reciprocate. Secured to the forward end of the cylinder 1 is the front head 3 having a recess in which is located an anvil block 4 which lies adjacent to the rear end of the drill steel 5. Surrounding the drill steel 5 is the chuck 6, inclosed within a rotating member 7 having gear teeth 8 provided on a portion of its surface. The member 7 and chuck 6 are rotated by means of a shaft 9 extending alongside the cylinder 1 from the rear end and provided at its forward end with a pinion gear 10 meshing with gear 8.

At the rear end of the cylinder 1 and preferably at one side is bolted a casing 11 in

which is located a rotating motor 12 comprising a pair of spur gears of equal diameter, as is usual in this form of motor. A shaft 13 is attached to one of the gears of the motor 12 having a gear 14 at its end. 60 This gear 14 is in mesh with a gear 15 provided on the rear end of the shaft 9. From the above description it will be seen that a construction has been provided whereby when motive fluid is supplied to the motor 12 the chuck 6 and consequently the drill steel 5 are rotated.

Referring to Fig. 3 of the drawings, the motor casing 11 is provided with depressions 16 on either side of the center line of the 70 casing. Within the depressions 16 are located bolts 17 whose heads 18 almost completely fill the depressions. In alignment with the recesses 16 are holes 19 provided for the shanks of the bolts 17 and directly 75 under the bolt holes 19 are lugs 20 provided as integral parts of the cylinder 1. The lugs 20 are bored as shown at 21, in Fig. 3, providing holes in alignment with recesses 16 and holes 19 in the motor casing 80 11, so that the bolts 17 extend through from the motor casing 11 through the casing and also through the lugs, and may be held firmly in place by suitable nuts 22 threaded to their lower ends. The construction is 85 such, as will be seen from the drawings, that the bolts must first be placed in position within the motor casing 11 before the gears 12 are inserted. This, however, is not objectionable as the motor casing 11 and motor 90 12 rarely require being disassembled after once being set in position in the tool, and this construction has the advantage that should the bolts break they may readily be removed and new ones substituted. 95

In rear of the motor casing 11 and cylinder 1 is the back head 23, clamped in any suitable way to hold the cylinder, front head, etc., in position, the method shown being the usual side rods 24 shown in Fig. 1. 100

A throttle valve 25 is located in the back head to admit motive fluid to the cylinder to reciprocate the hammer or piston 2 and also admits fluid through passage 26 to the rotating motor 12 the fluid to the motor 12 105 first passing through an automatic valve 27 to vary the quantity of fluid required by the motor.

It is to be understood that the present showing and description disclose only one 110

specific embodiment of the present invention, and that other forms and modifications are included within the spirit and scope of the invention, as expressed in the appended claims.

What I claim is:

1. In a percussive tool, a cylinder having a hammer therein, a rotating motor, a casing therefor secured to one side of the rear end of said cylinder, and a back head for said tool joining the rear ends of said cylinder and motor casing.
2. In a fluid operated percussive tool, a cylinder having a hammer therein, a rotating motor, a casing therefor secured to one side of the rear end of said cylinder, and a back head for said tool joining the rear ends of said cylinder and motor casing, said back head having motive fluid admitting means for said hammer and rotating motor.

3. In a percussive tool, a cylinder having a hammer therein, a rotating motor, a casing therefor secured to one side of the rear end of said cylinder, securing means for said motor casing comprising bolts extending through said motor casing and through projections provided on said cylinder.

4. In a percussive tool, a cylinder having a hammer therein, a rotating motor, a casing therefor secured to one side of the rear end of said cylinder, securing means for said motor casing comprising bolts having their heads set in recesses in said motor casing, said bolts extending through projections provided in said cylinder.

In testimony whereof, I have hereunto set my hand.

WILLIAM A. SMITH.

Witness:

ROBERT L. AMBROSE.
